UNITED STATES PATENT OFFICE.

ALBERT H. JOHNSON, OF WASHINGTON, DISTRICT OF COLUMBIA, ASSIGNOR TO NATIONAL ELECTRICAL SUPPLY COMPANY, OF WASHINGTON, DISTRICT OF COLUMBIA, A CORPORATION OF VIRGINIA.

DESIGN FOR A CASING FOR HAND-OPERATED GENERATORS FOR WIRELESS TELEGRAPHY.

48,638.

Specification for Design.

Patented Feb. 29, 1916.

Application filed September 23, 1915. Serial No. 52,323. Term of patent 3½ years.

To all whom it may concern:

Be it known that I, ALBERT H. JOHNSON, a citizen of the United States, residing at Washington, in the District of Columbia, have invented a new, original, and ornamental Design for a Casing for Hand-Operated Generators for Wireless Telegraphy, of which the following is a specification, reference being had to the accompanying drawing, forming a part thereof.

The figure is a perspective view of a casing for hand operated generator for wireless telegraphy, embodying the invention.

The casing comprises a cylindrical horizontal body portion 1, mounted upon a base

2. Extending upwardly beyond the cylindrical body portion 1 is a substantially vertical portion 3, which is substantially flat.

The numeral 4 designates webs serving to connect the portions 1 and 3. The top of the portion 3 carries a cap or cover 5, which is curved, as shown at 6.

I claim:

The ornamental design for a casing for hand operated generators for wireless telegraphy, as shown and described.

ALBERT H. JOHNSON.
